HUMMINGBIRD FEEDER

Peter Kilham, Barrington, R.I., assignor to Droll
Yankees, Inc., Foster, R.I.

Filed Apr. 9, 1973, Ser. No. 348,965

Term of patent 14 years

Int. Cl. D30—03

U.S. Cl. D30—14

FIG. 1 is a front elevational view of a hummingbird feeder showing my new design;

FIG. 2 is a top plan view thereof; and

FIG. 3 is a bottom plan view thereof.

I claim:

The ornamental design for a hummingbird feeder, substantially as shown.
